US0D1095734S

(12) **United States Design Patent** (10) Patent No.: **US D1,095,734 S**
(45) Date of Patent: ** Sep. 30, 2025

(54) **HANDGUARD AND HANDGUARD
COMPONENT FOR A FIREARM**

(71) Applicant: **Daniel Defense, LLC**, Black Creek,
GA (US)

(72) Inventors: **Nick Wisbath**, Pooler, GA (US); **Larry
Jones**, Ellabell, GA (US)

(73) Assignee: **Daniel Defense, LLC**, Black Creek,
GA (US)

(**) Term: **15 Years**

(21) Appl. No.: **29/923,607**

(22) Filed: **Dec. 29, 2023**

(51) LOC (15) Cl. **22-01**

(52) U.S. Cl.

USPC **D22/108**

(58) **Field of Classification Search**

USPC D22/103, 108, 109, 110; 42/75.02, 112,

42/106, 77

CPC F41A 21/00; F41C 23/16; F41C 23/12;
F41C 27/00; F41C 7/00
